UNITED STATES PATENT OFFICE

HENRY T. LANG, OF CLEVELAND HEIGHTS, OHIO, ASSIGNOR TO ELECTRIC VACUUM CLEANER COMPANY, INC., OF CLEVELAND, OHIO, A CORPORATION OF NEW YORK

FLOOR POLISHER

Application filed September 9, 1927. Serial No. 218,548.

The present invention relates to floor polishers which are adapted to be quickly applied to and removed from vacuum cleaners, and the object of my invention is to simplify 5 and improve the construction of such devices.

For a consideration of what I believe to be novel and my invention, attention is directed to the accompanying description and the claims appended thereto.

10 In the attached drawing which is illustrative of my invention, Fig. 1 is a view in side elevation of a vacuum cleaner; Fig. 2 is a similar view with certain of the parts broken away and the polisher mounted in position; Fig. 3 is a perspective view of the polisher; Fig. 4 is a view of a ratchet to prevent backward rotation of the polisher when the device as a whole is moved rearwardly; Figs. 5 and 6 illustrate details of construction; Fig. 7 is 20 a partial view in side elevation of a modified form of the invention; Fig. 8 is a partial view in front elevation; Fig. 9 is a perspective view of one of the frame supporting members, and Fig. 10 is a detail plan view partly in 25 section.

The application of a polisher to the type of vacuum cleaner illustrated is one which presents a peculiar problem in that the passage between the nozzle walls is relatively narrow 30 and furthermore instead of being straight is so curved or shaped that it is impossible to locate a driving belt therein. Nor is it feasible for mechanical reasons to secure the polisher directly to the nozzle, which is a long and relatively narrow casting.

Referring to Fig. 1, which illustrates a type of vacuum cleaner, 5 indicates the armature and 6 the field magnet of an electric motor which is enclosed in a casing 7. 8 indicates a suction fan which is mounted on the armature shaft 9 and is enclosed in a casing 10, the latter being united with the casing of the motor by screws. 11 indicates the aluminum nozzle which has a relatively narrow 40 and also curved passage 12 for the dust-laden air. The fan casing and nozzle in the cleaner chosen for illustration form a unit either being cast as one or otherwise united. For simplicity they may be referred to as the nozzle member. The passage 12 terminates at its

upper end in an enlargement or chamber 13 which is in communication with the suction side of the fan. 14 indicates the discharge conduit for the fan casing and 15 a cover for the conduit to decrease the load on the motor 55 by rendering the fan inoperative when the cleaner is used for polishing.

17 indicates the front floor wheels of which there are two. These wheels are mounted on crank arms 18, the connecting shaft portion 18^a of which is mounted in downwardly projecting lugs 19 which are formed as an integral part of the fan casing and project forwardly therefrom, Fig. 1. The position of the nozzle with respect to the floor can be 60 adjusted by means of the adjusting screw 19^a which acts on one of the crank arms. The rear end of the cleaner is supported by a single floor wheel 20 which is of the caster type and is free to swing about the vertical pivot 21. The device as a whole is moved about by a handle 22 which has a bail at the lower end, the latter being pivotally secured to the cleaner. 65

The floor tool, in this case a polisher 25, is 70 in the form of a brush having radial bristles which are stiff enough to support the weight of the front end of the cleaner without bending an appreciable amount. The brush is mounted on a spindle and the ends of the 75 spindle are located in bearings 26 which in turn are supported by integral depending portions 27 of a rectangular frame 28 which is open both at the top and bottom. The frame members are made of sheet metal and 80

are relatively narrow so as to expose the greater portion of the floor engaging tool. The top of the frame is provided with cross bars or bridges 29 which serve to stiffen the frame and also to carry vertical pins 30, 85 which, when the polisher is assembled in position, in the rear of the front wall of nozzle, engage the front of the rear lip 31 of the nozzle as best shown in Fig. 2 to hold the parts in their proper relative positions. 90 These pins serve to position the polisher frame and also to prevent rearward movement thereof. The rear member of the frame is provided with two spaced insets 32 and to each inset is riveted a substantially L-shaped 95 100

member 33, the upper portion of which has a slot 34 arranged to receive a thumb screw 35 located in a tapped hole, in the underside of the lugs 19 which form an integral part of the fan casing. These members being spaced apart by a considerable distance are well adapted to prevent the frame from twisting or working loose. It will be seen that the bottom or working end of the nozzle terminates in a plane below the lowest part of the fan casing and that by reason of the construction and arrangement of the polishing brush supporting frame, it bridges the space between the nozzle and the fan casing.

15 The polisher is provided with a central pulley 36 and is driven by a quarter turn belt 37 from a pulley 38 permanently mounted on the front end of the armature shaft. In order to permit the belt to connect the two pulleys an opening 39 is formed in the under or rear wall of the nozzle. During normal operation of the cleaner, this opening is closed by a hinged cover 40 and is retained in place by a small, flat spring 41 which snaps over the edge of the wall forming the opening 39. In order to retain the cover in its open position when the polisher is in use, a second spring 42 is provided which snaps over a projection 43 formed on the shaft 18^a which carries the crank arms for the floor wheels. The front wall of the cleaner is provided with an opening which is closed by a cover 44. By removing the cover the quarter turn belt 37 can be slipped over the pulley or removed.

35 In Fig. 4 is shown one of the bearings 26 which is provided with a ratchet which, for example, may comprise a number of hardened steel balls 45, cam faces 46 and coiled compression springs 47. This arrangement permits the brush to be freely driven in a forward direction by the belt 37 but prevents the polisher from being rotated in the opposite direction when the polisher as a whole is moved backward. Such an arrangement also prevents the belt 37 from being thrown off the pulley 38.

50 In order to prevent the polisher from marring furniture and baseboards the ends and corners are protected by strips of rubber, or equivalent material 48, which are secured to the frame by any suitable means, such as rivets.

Assuming that the cleaner has been used as such and it is desired to apply the polisher, the first step is to open the cover 40 in the under wall and retain it by snapping the spring 42 over the projection 43 on the shaft 18^a. The next step is to secure the L-shaped brackets in place by slipping the slotted ends under the heads of the screws 35. The bag is removed from the discharge conduit of the fan casing and the cover 15 applied. The cover 44 is removed and the belt 37 which is permanently mounted on the polisher is fished up through the opening 39 and mount-

ed on the pulley 38 after which the cover 44 is replaced and the polisher is ready for use.

To remove the polisher the various operations enumerated are reversed.

The rotation of the motor, subject to the control of the usual switch in the circuit, rotates the polisher in an anti-clockwise direction. This has the effect of pulling the device as a whole forward. When the user pulls the device rearwardly, the overrunning ratchet mechanism shown in Fig. 4 prevents the polisher from turning backward and throwing the belt off the pulley 38.

In Figs. 7 to 10 is illustrated a modification of my invention. In this case the front floor wheels 17 are mounted on fixed studs 50 and are non-adjustable although this feature has no bearing on the present case. These studs are screw-threaded into the lugs 19 which form integral parts of the fan casing as before. Secured in the lugs are supporting devices 51 which may if desired form extensions of the studs, as in the present case, or where the floor wheels are mounted as in Fig. 1 the supporting devices may take the form of the cross shaft 18^a. The rear wall of the frame is provided with two spaced members 33 as before but there are certain differences in construction. Each member has a slot 52 in its rear end to receive the supporting device 51 and about which it can turn as a pivot as will be described later. It extends forwardly to the polisher frame and has a right angle portion 53 which terminates just short of the rear or under wall of the nozzle. This portion is slotted and mounted above the slot is a flat spring 54, the lower end of which is shaped to engage or rest on the upper surface of the bead 55 on the nozzle, when the polisher is in use and hold the front end thereof. Each member is also provided with a second right angle member 56 and this is securely riveted to the rear member of the frame of the polisher. The under side of the nozzle is provided with a belt opening as before and which is normally closed by the cover. The cover differs somewhat in shape to conform to that of the underwall of the nozzle. It is held in its closed position by a flat spring 57 and in its open position by the flat spring 58, the latter being secured to the lower part of the fan casing.

In mounting the polisher in place the slotted ends of the members are slipped over the supporting devices 51 and are pushed inward until the devices occupy the bottoms of the slots after which the frame is slightly rotated about the devices as pivots, until it occupies the position shown in Fig. 7. As the flat springs 54 pass over the bead 55, they snap into place and thus hold the front end of the polisher frame in place against the nozzle. The polisher frame is in part held against endwise movement by the upstanding lugs 59 which are secured to the frame mem-

bers. The principal point of difference between the two constructions illustrated is that in the first form of the invention, the polisher is wholly supported by the lugs 19 and in the 5 second form the polisher is supported partly by the lugs and partly by the bead 55 on the nozzle.

By using an open frame for supporting the polisher and locating it in the position shown 10 the polisher can have any desired diameter and may be of a length equal to or greater than the nozzle, since the construction of the frame imposes no limitations in this particular. The nozzle in the type of cleaner illustrated as well as in many others, is relatively narrow and because of the fact that a belt cannot be located therein the polisher is set behind the nozzle with its axis substantially in line with the motor-driven pulley. Such 15 a construction provides a firm seating for the polisher frame both in the front and rear which is so necessary for this class of work. As an additional securing means the adjusting screw 19^a may, in the first described form 20 of the invention, be adjusted to force the floor wheels 17 into contact with the rear member of the frame. As these wheels are widely spaced they exert a restraining influence against twisting of the frame. The belt 37 which is 25 of rubber and being under appreciable tension 30 also assists in holding the frame in place.

It is important, if the best results are to be obtained, to have the entire weight of the front end of the cleaner supported directly by 35 the polisher since by so doing the full effect thereof as a polishing agent is obtained, and all questions of nice adjustment as the polisher wears are avoided as would be the case if 40 floor engaging wheels for the polisher were employed. The lugs 19 as above stated are formed as an integral part of the casing, and to partly conceal them and also to add finish 45 to the cleaner, they are covered by the flat members 49 which also extend to and are cast in one with the nozzle. This makes a very strong construction and eliminates all danger of breaking of the casting.

What I claim as new and desire to secure by Letters Patent of the United States, is:

50 1. In a vacuum cleaner having a nozzle, a fan casing and motor, the combination of a rectangular frame, the front of which is connected to the nozzle, means secured to the rear wall of the frame intermediate its ends for 55 connecting it to said casing, a rotary floor-engaging tool carried by the frame, and means driven by the motor for rotating the tool.

60 2. In a vacuum cleaner having a nozzle, a fan casing and motor, the combination of a rectangular frame the front of which is connected to the nozzle, spaced members secured to the rear member of the frame, supporting means carried by the casing which engage and hold the members thereby securing the 65 frame in place, a rotary floor-engaging tool

carried by the frame and supporting it and the front end of the cleaner, and a belt for transmitting motion from the motor to the tool.

3. In a vacuum cleaner having a nozzle, a 70 fan casing and a motor, the combination of a rectangular frame which is situated below the nozzle and in the rear of the front wall thereof, spaced rearwardly extending members carried by the frame, means for securing the members to the casing, means engaging the underside of the nozzle to position the front edge of the frame, a rotary floor-engaging tool carried by the frame, and a belt for transmitting motion from the motor to the tool. 75

4. In a vacuum cleaner having a nozzle which has an opening in its under wall, a fan casing, and a motor, a cover which normally covers the opening, the combination of a rectangular frame situated below the nozzle, 80 members on the frame which engage the nozzle to position the front part of the frame, slotted members on the rear portion of the frame, means carried by the casing which hold the members in place, a rotary tool carried by the end members of the frame, and a belt which transmits motion from the motor to the tool and extends through the normally-closed opening in the under wall of the nozzle. 85

5. In a vacuum cleaner having a nozzle member which has an opening in its under wall, and a motor, a cover for normally closing the opening, the combination of an open, rectangular frame, lugs which are fastened to the rear member of the frame, bridges connecting the front and rear members of the frame, means carried by the bridges which engage one of the nozzle lips to position the front part of the frame, clamping screws which are carried by the nozzle member and 90 engage the lugs for securing the frame in place, a rotary floor tool carried by the frame, and a belt which passes through the opening in the nozzle wall for transmitting motion 95 from the motor to the tool. 100

6. In a vacuum cleaner having a nozzle with a normally closed opening in its under wall, a fan casing, uniting means which serve in part to unite the nozzle and casing, and a motor, the combination of a frame which is open top and bottom, supporting means carried by the frame, clamping screws for securing the frame to the uniting means, a rotary floor-engaging tool carried by the frame 115 which forms the sole support for the weight of the front end of the cleaner, and a means for transmitting motion from the motor to the tool which extends through said opening in the under wall of the nozzle. 120

7. In a vacuum cleaner having a fan and casing, a motor for driving the fan, a pulley on the motor shaft, a nozzle having a normally covered opening in its front wall through which opening a belt may be mounted on the pulley, a second normally covered open- 125 130

ing in the rear wall of the nozzle through which a belt passes, the combination of a frame which is secured to the underside of the cleaner, a floor tool mounted for rotation in the frame, a pulley for the tool, and a driving belt which extends downwardly through the said second opening and connects the two pulleys.

8. In a vacuum cleaner having a fan and casing, a nozzle extending downwardly from the casing, a fan, a motor for driving the fan, the combination of a detachable frame located under the front end of the cleaner, means for securing the rear part of the frame to the fan casing, means for holding the front end of the frame in predetermined position with respect to the nozzle, a rotating floor-engaging tool carried by the frame, and a device for transmitting power from the motor to the tool.

9. In a vacuum cleaner having a fan and casing, a motor for driving the fan, a nozzle in front of the fan casing which extends downwardly and terminates in a plane below the casing and is spaced therefrom, the combination of a frame in which a floor tool is supported, said frame bridging the space between the bottom of the nozzle and the fan casing, means for securing the frame in said bridging position, a floor-finishing tool mounted in the frame, and means for transmitting power from the motor to the tool for rotating it.

In witness whereof, I have hereunto set my hand this 6th day of September 1927.

HENRY T. LANG.
